UNITED STATES PATENT OFFICE.

FRANCIS MORLEY WARD, LEONARD CHARLES BYGRAVE, AND HENRY JAMES HERINK, OF LONDON, ENGLAND, ASSIGNEES TO THE RELAY AUTOMATIC TELEPHONE COMPANY, LIMITED, OF LONDON, ENGLAND.

AUTOMATIC TELEPHONE SYSTEM.

1,359,940.

Specification of Letters Patent. Patented Nov. 23, 1920.

Application filed September 13, 1917. Serial No. 191,174.

To all whom it may concern:

Be it known that we, FRANCIS MORLEY WARD, LEONARD CHARLES BYGRAVE, and HENRY JAMES HERINK, subjects of the King of Great Britain, all residing at Marconi House, Strand, London, England, have invented new and useful Improvements in Automatic Telephone Systems, of which the following is a specification.

10 Our invention relates to automatic telephone systems and the automatic part of semi-automatic telephone systems in which apparatus common to groups of lines are used. In such systems groups of lines are 15 used for connecting one line to one of a plurality of other lines and auxiliary apparatus is common to the group. It is necessary, when the traffic is considerable, to give the calling lines access to or to make available 20 a plurality of auxiliary apparatus and exclusively to associate one of such common apparatus with the calling line during the impulsing or connecting period and to render other common apparatus available to 25 other potential calling lines.

In systems in which impulse senders of the uncontrolled type have been employed, and in which the impulse responders or the like are accessible to a plurality of lines, the 30 time of engagement of such responder may be considerable owing to the tardy or faulty operation of an impulse sender. The object of this invention is to reduce this engaged time to a minimum by so arranging the responders that they are not engaged or exclusively associated with a calling line until the sending of the impulses commences, and that they are disengaged at the end of the impulsing.

40 The invention is illustrated by its application to calling lines having access to impulse responders which are then exclusively associated therewith and determine with which group of lines corresponding with the 45 digit impulses set up by the caller a calling line is to be connected; but the invention is not limited to such arrangements as it is also applicable to the picking up of anyone of a plurality of common apparatus, such as 50 registers and the like.

It is known that one of a plurality of common devices can be exclusively associated with a calling line by sending an impulse prior to the digit impulses but this

invention obviates the necessity of such an extra impulse and is applicable to a system using well known impulse sending devices on any system.

According to this invention when a subscriber's line is extended to a trunk line at 55 a digit switching stage, a selector or impulse responder in a bypass of the trunk is tentatively associated with the trunk line and prepared to receive the impulses. If now the caller delays to send impulses and another caller in the same group removes his telephone to call, his extended line will be connected in parallel to the same responder and the first to send an impulse will exclusively associate the responder with his line 60 while the other calling line will be tentatively associated with another responder in another bypass. The first impulse of a digit thus exclusively associates one of a plurality of responders with the calling line and allows it to receive further impulses. The 65 first impulse, although used primarily as described, is effective for calling digit No. 1 in combination with the normal contacts of the responder, and also as hereinafter described. Should only one impulse be required to select the desired number, the responder goes through its cycle of operations and the wanted subscriber is marked 70 through the resting contact of the first responder relay or more positively as herein-after described, after which the responder is released and becomes available for other calls.

By such an arrangement the responder 75 relays are prepared in advance so that a minimum number of relays has to operate between the first and second impulses. On the completion of the digit impulses the impulse responder and its bypass are automatically disconnected from the trunk and are therefore free to be taken into engagement by another calling line.

85 Arrangements are provided for insuring that, if all the responders associated with a group of lines are engaged and another calling line is waiting, the retained responder relays are released before the responder is re-prepared.

90 The invention is illustrated by the drawings in which Figure 1 shows the arrangement when two responders are provided for a group of lines; Fig. 2 shows a modifica-

tion suitable for large systems in which the impulses are repeated at each stage; and Fig. 3 shows a modification for use at a final stage requiring responders which respond to two series of impulses.

Figs. 4 and 5 are diagrams showing how the connecting apparatus may be arranged.

Fig. 1 shows one form of the invention whereby a group of trunks has access to two responders. Only two trunks are shown (T1 and T2) though any number could be connected to *a*, *b*, *c*, *d*, etc., *a*1, *b*1, *c*1, *d*1, etc., and *p* in a similar manner to those shown; the six relays shown in line with each trunk are individual to that trunk. Only one responder S1 is shown, the other S2 being an exact duplication and connected to *a*1...*f*1 in a similar manner.

The subscriber is connected to the trunk by any suitable pre-selecting means in a known manner and the impulse relay 1E operates when a subscriber's line is extended to a trunk over circuit 1. Guarding relay 2E is operated over circuit 2. Circuit 3 is now completed to prepare the responder, the slow release relay 3E energizing provided the responder is disengaged. This completes circuit 4 and all the M relays operate.

The subscriber now operates his dial and breaks 1 a number of times equal to the value of the digit to be called, say, 7. On the first impulse 1E releases and 5E operates over 5 and holds over 6 for the duration of the impulse. 7E now operates over 7. At the end of the impulse 1E again operates and breaking 6 releases 5E. 7E now holds over 8 and operates 8E. The latter changes the line *p* over to the second responder by *f* to *e*1 and breaks line *a* so that if any calls are made while S1 is in use, S2 will be prepared and used.

The second impulse deenergizes 1E and completing 9 operates A1, which locks over 10. M1 now holds over 11 (which follows the same path as 9 to 1E). When 1E re-energizes 9 is broken and M1 releases. The third impulse operates A2 over 12, M2 holding over 13 (as in the case of 12 to 1E). On 1E reenergizing M2 releases. This breaks 10 and A1 releases thus re-operating M1 over 4.

A similar series of operations takes place for each impulse, the sixth impulse operating A5 and releasing M5. On the seventh impulse 14 is completed and A1 again operates. This completes 15 and 15E is operated, locking over 15a. At the end of the impulse M1 releases, and this releases A5 and re-operates M5.

During the impulses 3E has been maintained by the impulses over the front contact of 8E, so that after the last impulse of a series has ceased it deenergizes, 16 is completed and apparatus associated with subscriber No. 7, or the seventh group if

it is a large system, is brought into action. Simultaneously, the relay 17E of the trunk is operated (circuit 17) and the required subscriber (or group) is connected to the trunk by any known means, usually through condensers to the lines marked 18, so that the speaking circuit is established. 17E also breaks 8, releasing 7E and 8E, and any responder relays that may be energized. 17E locks over 17a as long as the trunk is engaged. When a selector is engaged the common circuit 7 is opened at 8E so that no other relay 7E can energize.

On the subscriber clearing, 1E deenergizes, and then 2E, releasing 17E when the trunk is ready for further calls.

The switch P is provided in order that selector S2 may, if desired, be taken into use before S1, the latter only being used when S2 is engaged. This switch can be used to equalize the work over the selectors, and is also useful if S1 should become faulty.

Fig. 2 shows another form of the invention which is more suitable for the digit stages of a large system. It is usual in such systems to transmit the impulses from stage to stage over the A and B speaking lines to operate the responder at the various stages, the impulses being given by completing the loop. A retaining wire is used to maintain the switches at each stage.

In the figure only two trunks are again shown (T1 and T2), the responders being connected to *a*, *b*, *c*, *d*, *a*1, *b*1, *c*1, *d*1 and *p* in the same manner as described for Fig. 1. The five relays in line with each trunk are individual to that trunk.

When the call is extended to the stage under consideration, an earth is connected to the retaining wire, circuit 1 is completed and 1E1 operates. This earths *p* (circuit 2) and prepares the selector as already explained for Fig. 1. On the first impulse the lines AB are connected together and 3E1 operates (circuit 3) locking over 4 to the retaining wire. This changes the circuit of 1E1 to the A line circuit 5, so that it only remains energized during the impulse. When 3E1 energized 6 was completed over responder No. 1, if free, and 7 over responder No. 2 if the former were engaged. In the former case 6E is energized, locking over 8. At the end of the impulse 1E1 releases and the remaining impulses operate the responder over 9 and line *d*. When a selector is engaged, the common circuit 6 is opened in a manner similar to 7 in Fig. 1, so that no other relay 6E can energize; circuit 7 is therefore complete for 7E1. The responder operates as described in connection with Fig. 1, and at the end of the impulses line *b* is earthed as before. 10E operates over 10 and locks over 11 to the retaining wire in a manner analogous to 17E of Fig. 1. This breaks 4 and releases 3E1 and 6E and the responder is 130

released, the AB and retaining wires being extended to the next switching stage in any known manner. When the subscriber clears, the retaining circuit is broken and 10E deenergizes, the trunk thus being free for further calls.

It will be readily understood that either of the arrangements shown in Fig. 1 or Fig. 2 can be extended to give the trunks access to three or more responders.

Fig. 3 shows another modification which is particularly suitable for the final stage where a two digit impulse responder is usually necessary. Only one trunk is shown and means for connecting to three responders is provided. Only one responder is shown, the other two being similar and connected in an exactly similar manner to $a_1, b_1, c_1, d_1, a_2, b_2, c_2, d_2$. The lines $a, b, c, d, a_1, b_1, c_1, d_1$ and the like can be multiplied to any number of trunks. The circuit will be described for a system in which the impulses are transmitted over the A and B lines, as in Fig. 2, though it will be readily understood that in the case of a 100 line board the responder would be directly operated from the impulse relay as in Fig. 1. When the call is extended to the trunk 1E^x operates off the retaining wire (circuit 1). This completes 2 if the first responder is free and 2E^x and 3E^x operate. If S1 is engaged this circuit is broken by 12E and so 4 would be completed if S2 is free, operating 4E and the relay associated with S2.

In a similar manner connection is established with responder S3 if both S1 and S2 are engaged. The operation of 3E^x prepares the responder by operating all the M relays (circuit 5). 6E^x is also operated (circuit 6) and 3E^x locks itself over 7. In order to make the operation of the responder similar on both trains of impulses, one impulse is given to the responding relay A (to make up for the one absorbed by the trunk picking up a responder) by completing circuit 8 and operating A1, which locks over 9. On the first impulse the loop is completed over the A and B wires and 10E^x is operated (circuit 10), 1E^x being maintained for the duration of the impulse over 11 (1 being broken by 10E^x). 12 is completed holding up 10E^x and 2E^x while the selector is in use and operating 12E. This latter changes 6E^x to the impulse wire circuit 6a, so that it will release when the impulses cease. 12E also breaks line b so that no trunk can connect to the responder. At the end of the first impulse 1E^x releases.

The second impulse operates A2 (circuit 13) M2 releasing at the end of the impulse, as explained for Fig. 1. The remaining impulses operate A3, A4 and the like, as before explained. 14E operating on the sixth impulse (circuit 14) and locking over 15.

At the end of the series of impulses, 6E^x

deenergizes, say, after six impulses have been sent. The negative (circuit 7) is removed from 3E^x, which holds over 16, (circuit 7 was previously a short circuit on relay 16E and prevented it operating) operating 16E (as A1 is the only A relay retained energized). On 16E operating, 9 is broken and A1 is released, reenergizing M1. When A1 releases, 16 is broken and 3E^x releases, 16E holding over 17. 6E^x is reenergized over 18.

The first impulse of the second series operates A1 over 19, and this retains over circuit 20 operating 20E. The latter changes 6E^x to the impulse wire over 6c and 6a. The relays A2, A3 and the like operate in turn as before, 21E operating on the sixth impulse (circuit 21) and locking over 22. At the end of the impulses 6E^x releases and completes 23 operating 23E. In order to prevent two responders marking out at the same time 23E is double wound, the second winding being normally connected to a test wire T. This wire is connected in a similar manner to each responder and if any responder is marking out (that is, has its 23E relay energized) negative is connected to T. This prevents the 23E relay of any other responder energizing as current flows through both windings, and these neutralize one another. When 23E operates, the initially energizing tens and units circuits 24 and 25 are completed and by means of a "marker" (see British specification No. 4819 of 1914) or other apparatus connection between the trunk line and the wanted subscriber is established. At the same time 26E is operated over 26, locking over 27. This releases 10E, 2E, 12E and all the responder relays, so that the responder is free to receive impulses from other trunks.

With the circuit arrangement shown in Fig. 3 the responders themselves have no definite order of precedence, the responders to which a line has access and their order of precedence being determined by the connecting apparatus associated with the line. It is therefore possible to give different lines access to different responders and also to the same responder, or to give different lines precedence to different responders.

For example, Fig. 4 of the drawing illustrates one method of arranging the connecting apparatus. The lines are shown divided into six sub-groups a_1 to f_1 which may each consist of a plurality of lines, though only one is shown. Each line can obtain access to three responders, the sub-group a_1 having access to responders 1, 4 and 6, in the order named. By such an arrangement an efficiency, nearly equal to that when each line has access to all responders, is obtained, though the connecting apparatus is greatly reduced.

Fig. 5 illustrates by way of example one

arrangement whereby different lines, or sub-groups of lines (*a*1, *b*1 and *c*1) give precedence to different responders. For instance, the line *a*1 will use responder 2 if all responders be disengaged, whereas *b*1 would use 3 and *c* would use 1. Line *a*1 would only use 3 if 2 were engaged and 1 if both 2 and 3 were engaged. In this way the work is equally distributed over the responders.

We do not limit the application of the invention to full automatic systems, as it can be applied to semi-automatic systems, for instance, those in which the responders are set by manual operators by means of key sets, dials or the like.

What we claim is:—

1. In a telephone system, the combination of a number of subscribers' lines, an impulse sender for each line, a numerical impulse responder accessible in common to a plurality of the lines and means whereby the first impulse is caused to associate the responder exclusively with the line over which the impulse is sent and to be numerically effective.

2. In a telephone system, the combination of a number of subscribers' lines, an impulse sender for each line, a number of trunks accessible in common to each subscriber's line, a number of by-paths smaller than the number of trunks, numerical impulse responders in the by-paths, means whereby on a line being extended to a trunk a by-path is tentatively connected to a trunk, means whereby the first digit impulse coming in over a subscriber's line and a trunk associates the responder with that trunk to the exclusion of other trunks and means whereby on the completion of the digit impulses the by-path and responder are disconnected from the trunk.

3. In a telephone system, the combination of a number of subscribers' lines, a plurality of numerical impulse responders each of which is accessible in common to a plurality of the lines, means for exclusively associating a responder with a line, means whereby, on another line being taken into engagement, a second responder is prepared, and means whereby, should the first responder

be released before the other responder is exclusively associated with the second line, the first responder is re-prepared and the second responder is returned to normal.

4. In a telephone system, the combination of a number of subscribers' lines, a numerical impulse responder accessible in common to a plurality of the lines, means whereby, on one of the lines being taken into engagement, the impulse responder is connected to that line, and means for breaking the connection on the responder being taken into engagement by another line before being taken into engagement by the first line.

5. In a telephone system, the combination of a number of subscribers' lines, a plurality of numerical impulse responders each of which is accessible in common to a plurality of the lines, means whereby, on one of the lines being taken into engagement, one of the impulse responders is connected to that line, means whereby a second line can take said responder into engagement, means for breaking the connection between the first line and said responder and means for connecting the first line to a second responder.

6. In a telephone system, the combination of a number of subscribers' lines, an impulse sender for each line, a numerical impulse responder accessible in common to a plurality of the lines, means whereby the first impulse is caused to associate the responder exclusively with the line over which the impulse is sent, and a slow acting relay forming part of the responder and dependent on the first and all succeeding impulses.

7. In a telephone system in which a responder is not normally associated with a line, the combination of a number of lines, a plurality of numerical impulse responders actuated directly by the subscriber's dial impulses each of which is accessible in common to a plurality of the lines for the purpose of setting up but not maintaining a connection, a distributing field between the lines and the responders and means for associating a responder exclusively with a calling line.

FRANCIS MORLEY WARD.
